CLAIM

The ornamental design for a combined alarm clock, tissue case and photo frame, as shown and described.

DESCRIPTION

FIG. 1 is a front and top-right perspective view of a combined alarm clock, tissue case and photo frame showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side view being a mirror image.

FIG. 1

FIG. 2

FIG. 3

FIG. 4

FIG. 5

FIG. 6
